CLAIM

The ornamental design for a mobile terminal with graphical user interface, as shown and described.

DESCRIPTION

FIG. 1 is a first embodiment of a mobile terminal with graphical user interface showing our design; and, FIG. 2 is a second embodiment of the mobile terminal with graphical user interface.

The broken lines showing portions of the mobile terminal form no part of the claimed design. The broken lines showing elements on the mobile terminal illustrate portions of the graphical user interface that form no part of the claimed design.
